(57) **CLAIM**

The ornamental design for a motor actuator, as shown and described.

DESCRIPTION

FIG. 1 is a front view of a motor actuator.

FIG. 2 is a rear view of the motor actuator.

FIG. 3 is a left side view of the motor actuator.

FIG. 4 is a right side view of the motor actuator.

FIG. 5 is a top plan view of the motor actuator.

FIG. 6 is a bottom plan view of the motor actuator.

FIG. 7 is a top perspective view of the motor actuator; and, FIG. 8 is a bottom perspective view of the motor actuator.

The broken lines shown in the drawings illustrate environmental structure and portions of the motor actuator that form no part of the claimed design.
